UNITED STATES PATENT OFFICE.

JACOB KINDERMANN, OF LEIPZIG, GERMANY.

DESTRUCTION AND DEODORIZATION OF SMOKE.

1,024,204.

Specification of Letters Patent.

Patented Apr. 23, 1912.

Application filed August 1, 1910. Serial No. 574,998.

To all whom it may concern:

Be it known that I, JACOB KINDERMANN, a subject of the King of Saxony, residing at Leipzig, Germany, have invented certain new and useful Improvements in the Destruction and Deodorization of Smoke, of which the following is a specification.

This invention relates to the destruction and deodorization of smoke.

10 The smoke and other gases of combustion are conducted into a receptacle where they are admixed with a large quantity of air under pressure which excessively dilutes the smoke so that, when the mixture comes out 15 of chimney the smoke is no longer visible. In said receptacle porous bodies are arranged which partly absorb the bad smell.

In the accompanying drawings the invention is shown applied to the exhaust of a 20 motor car and further to a chimney.

Figure 1 represents the receptacle in longitudinal section. Fig. 2 shows a motor car in side view having the apparatus mounted on its exhaust.

25 The receptacle 1 which may be of any convenient material has an inlet 2 which communicates with the exhaust 3 of the engine. Partitions 5 are fixed at either side in said receptacle 1, so that between the two 30 partitions of every pair of partitions only a small space 10 is left free. The partitions fixed with one end at the one wall of the receptacle terminate a short distance from the opposite wall so that alternately at the right 35 and at the left side of the receptacle small passages 6 are formed; in said passages deflecting pieces 7 are arranged. Said partitions 5 divide the receptacle into a certain number of superposed compartments 8¹, 8², 40 8³, 8⁴, 8⁵, 8⁶ which decrease in height from the bottom to the top. Between the fixed ends of every pair of partitions 5 openings 9 are provided in the walls of the receptacle through which air can flow in. This air 45 comes from chambers 11 to which air under pressure is supplied from the air compres-

sor 16. In the top plate of the receptacle 1 an outlet pipe 12 is mounted. A pipe 13 serves for conducting the air under pressure from the tank 15 to the air chambers 11. 50 The air pump 16 for the tank 15 is operated from the engine in any suitable manner. A stop cock 17 is provided for shutting off the air tank from the air-chambers.

This apparatus is mounted at the rear 55 end of a motor car in convenient manner (Fig. 2).

In one or more of the compartments 8 of the receptacle 1 blocks 18 of porous material are arranged which are destined to 60 partly absorb the smell of the exhaust gases. The support in which said blocks are removably mounted is easily accessible by means of the door 19. The gases could however be deodorized by means of chemicals 65 admixed with the compressed air.

I claim:

An improved device for the destruction and deodorization of smoke, comprising in combination with the exhaust for the smoke, 70 a casing having an inlet in its bottom plate communicating with said exhaust, and an outlet for the invisible gases in its top plate, hollow shelves extending alternately from opposite sides of the casing and leaving 75 spaces between their free edges and the casing, the hollow shelves having an opening along their free edges for the outlet of compressed air fed to the space in the shelves through holes in the casing communicating 80 with compressed air chambers placed outside thereof, and baffles placed in the space between the outer edges of the shelves and the casing wall, substantially as described and shown and for the purpose set forth. 85

In witness whereof I have hereunto set my hand in the presence of two witnesses.

JACOB KINDERMANN.

Witnesses:

MAX RECKNAGEL,
HANS RICHTER.
